UNITED STATES PATENT OFFICE.

RALPH V. SAGE, OF WESTMONT, PENNSYLVANIA.

METAL SHEET-PILING.

No. 836,832.

Specification of Letters Patent.

Patented Nov. 27, 1906.

Application filed September 27, 1905. Serial No. 280,281.

To all whom it may concern:

Be it known that I, RALPH V. SAGE, a citizen of the United States, residing in the borough of Westmont, in the county of Cambria and State of Pennsylvania, have invented certain new and useful Improvements in Metal Sheet-Piling; and I do hereby declare the following to be a full, clear, and exact description of the invention, such as will enable others skilled in the art to which it appertains to make and use the same.

My invention relates to sheet-piling constructed of rolled or pressed metal shapes provided with locking means at their contiguous edges; and my object is to provide a metal sheet-piling composed of pieces which can be readily driven in close contact and locked at the same time and which can also be arranged with means for calking the joints, so that when necessary the piling may be made water-tight.

A further object is to provide a metal sheet-piling comprising rolled pieces or sections that can be used as rolled without any riveting, in co-operation with other rolled pieces or sections which require only a very small amount of riveting.

Referring to the annexed sheet of drawings, which form part of this specification, and in which like figures refer to like parts, Figure 1 is a sectional plan of a portion of my improved sheet-piling, showing several pieces thereof joined at their contiguous edges and at a corner. Figs. 2 and 3 are enlarged sectional views of the co-operating pieces or piles that form my improved sheet-piling. Fig. 4 is a sectional plan of a portion of the sheet-piling shown in Fig. 1, arranged with means for calking the joints to make the joints water-tight.

Referring to Fig. 2, the main pieces of the sheet-piling are composed of a trough or channel shape having a web 1, flanges 2, extending substantially at right angles to the web, and flanges 3, extending from the edges of flanges 2 in directions substantially at right angles to said flanges 2 and approximately parallel to said web.

The alternate pieces (shown in Fig. 3) are composed of a trough or channel shape, having a web 4 and side flanges 5 and are, provided with a splicing and locking strip 6, secured to the web 4 by one row of rivets.

The sheet-piling is constructed by driving the individual pieces or piles separately in

the usual manner, so that one flange 3 of each main piece projects under the splicing or locking bar 6 of the adjoining alternate piece, as clearly shown in Fig. 1.

The bar 6 is arranged with an integral filler 6c 7 of slightly greater thickness than the flanges 3 of the main pieces in order to provide a small clearance, and thereby facilitate the driving of the piles. It will be readily understood that the integral filler 7 can be made 65 from a separate piece of plate secured under the splicing and locking bar 6, without departing from this invention.

The corner connections are very simply and readily made by securing a Z-bar 8 to 70 the web 1 of one corner-pile, so that the web and the free flange of the said Z-bar are parallel, respectively, to the flange 2 and the flange 3 of the said pile, there being a certain space left between the said parts for the reception and locking of the flanges 2 and 3 of the contiguous pile, all as clearly illustrated in Fig. 1.

In the modification shown in Fig. 4 the splicing or locking bar 6 is provided at each 80 edge with a projecting flange 9, substantially at a right angle therefrom, and therefore parallel to the flanges 2 of those piles adjoining the pile that carries the said bar 6. The said flanges 9 are located, however, at a small 85 distance from the said flanges 2 in order to provide space for inserting calking material (indicated as 10) to make the sheet-piling water-tight when required.

From the foregoing description it will be 90 noted that my improved sheet-piling is very simple and economical and only every alternate piece thereof requires any riveting. Furthermore, the shapes used can all be rolled and the riveting can be done by machinery.

The sections and arrangement of parts shown may, of course, be slightly modified without departing from my invention as defined by the scope of the appended claims.

Having thus fully described my invention, what I claim, and desire to secure by Letters Patent, is -

1. In a metallic sheet-piling, a section composed of a substantially rectangular channel shape provided with a splicing and locking bar secured to the web thereof, said splicing and locking bar being formed of a flat portion arranged with an offset narrower than said flat portion.

2. In a metallic sheet-piling, the combination of a section composed of a substantially rectangular channel shape provided with a splicing and locking bar formed of a flat portion having an offset narrower than said flat portion, with coöperating sections each formed of a trough or channel shape having integral outward flanges projecting from the edges of its side flanges, said outward flanges being arranged to extend between the web and the splicing and locking bars of the contiguous sections.
3. In a metallic sheet-piling, a splicing-strip formed of a flat plate arranged with an offset, narrower than the said plate, and secured to the web of a channel-section of the sheet-piling for the purpose of locking the side flanges of the sections contiguous thereto.
4. In a metallic sheet-piling, a corner-section composed of a trough or channel section having parallel side flanges and integral outward flanges projecting from the edges thereof, a Z-bar secured to the web of said section by one of its flanges and arranged so that its web and extending flange are substantially parallel to and at a short distance from the side flange and outwardly-projecting flange respectively of the section aforesaid, whereby the side and outward flange of the contiguous corner-section are received between the extending flange and the web of the said Z-bar and the end and side flanges of the first said corner-section.
5. In a metallic sheet-piling, a section composed of a substantially rectangular trough or channel shape having a calking and locking strip secured to the web thereof, said strip being formed of a flat plate provided with end flanges and an offset on the side opposite to said flanges narrower than the said plate.
6. A metallic sheet-piling, comprising main sections each formed of a trough or channel shape having parallel side flanges and integral flanges projecting from the edges thereof, alternate sections composed of a trough or channel shape having parallel side flanges and provided with a calking and locking strip secured to the web thereof, said strip being formed of a flat plate provided with end flanges and an offset on the side opposite to said flanges narrower than the said plate, whereby the calking and locking strip is adapted to project over the outward flanges of the sections contiguous to the said alternate sections, while a calking-space is provided between the end flanges of the said strip and the adjacent side flanges of the contiguous sections.

In testimony whereof I hereto affix my signature in the presence of two witnesses.

RALPH V. SAGE.
